BROOKS H. TUNE, OF SHERMAN, TEXAS, ASSIGNOR OF ONE-HALF TO GEORGE W. TUNE,
OF SHERMAN, TEXAS.

SHADE-ROLLER BRACKET.

1,046,406.

Specification of Letters Patent.

Patented Dec. 3, 1912.

Application filed June 8, 1912. Serial No. 702,624.

To all whom it may concern:

Be it known that I, BROOKS H. TUNE, a citizen of the United States, residing at Sherman, in the county of Grayson and 5 State of Texas, have invented certain new and useful Improvements in Shade-Roller Brackets, of which the following is a specification.

This invention relates to window-shade 10 brackets; and its object is to provide a device of this character which is adjustable to shades and windows of different widths, also attachable to window casings at any desired point, without the use of screws or nails 15 commonly employed at the present time for securing curtain-fixtures to the casings of windows.

The invention also consists of certain other 20 novel features of construction and combinations of parts which will be hereinafter more fully described, and pointed out in the claim.

Reference is to be had to the accompanying 25 drawings, forming a part of this specification, in which similar letters indicate corresponding parts throughout the several views.

In said drawings, Figure 1, is a front elevation showing the invention applied to the 30 casing of a window; Fig. 2, is a top plan view of the device; and Fig. 3 is a detail view of one of the shade hangers.

Referring to the figures, A, A¹, are overlapping metal bars or strips, both being flat so that one can slide upon the other. The 35 inner bar A¹, carries a sleeve B at its inner end constituting a guide for the other bar, whereby the two are slidably bound together, permitting of longitudinal adjustment. It is provided with a series of longitudinally arranged round perforations C, through which a hook D, formed on the inner end of bar A is adapted to enter, and by which, with the perforations C, approximate adjustment to the widths of windows 40 is attained. The other end of the bar A has an outwardly bent portion E, and a clamping bar F carries a similar outwardly projection F¹, both projections being perforated

and joined by a bolt G, for connecting the adjacent ends of the two bars. The outer 50 end of bars A¹, and F are bent to provide inwardly projecting clamping-jaws H, said jaws being adapted to be securely forced against, or into the edges of the window casings by the bolt G, which serves to bind both 55 in adjusted position, as shown in Fig. 2, and thereby rigidly connecting the fixture to the window without the aid of nails or screws. Each of the said bars A¹, and F carries 60 a sleeve I sliding thereon, each sleeve carries a shade hanger I¹, and it will be understood that these hangers are adapted to receive and hold the ordinary construction of spring roller now in use.

In fastening the herein-described device 65 to the casings of a window, the bars A¹, and F are adjusted longitudinally, so that the jaws H thereof will loosely contact the outer casings; the parts can then be tightened in 70 adjusted position by means of the bolt G. The sleeves I may then be adjusted so as to bring the shade hangers I¹, at desired distances apart to fit the shade-roller.

The preferred form of the invention has 75 been outlined and set forth in the foregoing description; but I do not limit myself thereto, as I am aware that modifications may be made therein without departing from the spirit or sacrificing the advantages thereof, and I therefore reserve the right to make 80 such changes as fairly fall within the scope of the claim.

Having thus fully described my invention, 85 what I claim as new, and desire to secure by Letters Patent, is—

A shade-roller bracket, consisting of an inner and outer bar slidably joined by a sleeve on the former; said inner bar carrying a slidably mounted shade hanger and provided with a series of round perforations 90 spaced in horizontal alinement; and its outer end provided with an inwardly projecting clamping-jaw; the outer bar having a hook formed on its inner end adapted to enter said perforations in the inner bar, for their 95 approximate horizontal adjustment, and an

outwardly projecting lug at the other end; together with a clamping bar carrying a 5 slide shade hanger, an inwardly projecting clamping-jaw at its outer end, and an outwardly projecting lug at the inner end thereof; the lugs of the outer bar, and clamping bar being perforated and joined by a bolt for connecting their adjacent ends and

forcing the respective jaws securely against the outer edges of the window casings. 10

In testimony whereof I affix my signature in presence of two witnesses.

BROOKS H. TUNE.
